(57) **CLAIM**

The ornamental design for a stand for container, as shown and described.

DESCRIPTION

FIG. 1 is a perspective view of the stand for container;
FIG. 2 is a side elevation, the opposite side being a mirror image thereof;

FIG. 3 is a front end elevation thereof;

FIG. 4 is a rear end elevation thereof; and,

FIG. 5 is a top plan view thereof.

The broken line showing on FIGS. 1-5 is for illustrative purposes only and forms no part of the claimed design.

The container shown in phantom lines does not form part of the design. The bottom view is plain and does not form part of the design.
